UNITED STATES PATENT OFFICE.

THEODORE P. GARANKIN, OF NEW YORK, N. Y., ASSIGNOR OF ONE-HALF TO BRUNO A. MUELLER, OF NEW YORK, N. Y.

AUTOMATIC RECORDING DEVICE FOR HENS.

Application filed December 1, 1927. Serial No. 237,058.

My invention relates to automatic recording devices for hens and has a particular reference to devices adapted to leave imprints or marks specific for each particular hen, every time when this hen has laid an egg.

For this purpose I provide a small device which can be attached to the hen's foot and which has a printing button suspended 10 on a spring. This button is adapted to touch the ground when the hen springs down from a certain height. In order to properly use this device I provide specially arranged nests from which the hen must spring on 15 special pad with paper or similar material and a carbon paper or similar medium. The button strikes this pad and the engraved number or symbol on the button leaves an imprint on the record-receiving material 20 through the carbon paper.

My invention is more fully described in the accompanying specification and drawing in which—

Fig. 1 is an elevation partly in section of 25 a nest with a record-receiving device, Fig. 2 is a partial plan view of same, Fig. 3 is a plan view of a modified arrangement of a record-receiving device, Fig. 4 is a side view of same, Fig. 5 is a sectional view of same, 30 Fig. 6 is a sectional elevation of a recording device for a hen's foot, Fig. 7 is an end view of same, Fig. 8 is a view showing this device attached to a hen's foot, and Fig. 9 is a sectional view of a modified record-receiving pad.

My device consists of a tube 1 preferably made of some light metal, such as aluminum. This tube is open on top and partly closed 40 at the bottom. A plunger rod 2 is placed inside of this tube and extends outside through partly open bottom portion of the tube. A heavy button 3 is attached to the lower end of the plunger and a bushing or nut 4 to the top end.

The button 3 is provided on its lower surface with symbols or figures 5 identifying a particular hen. These figures are raised 45 above the button surface so as to leave corresponding marks on a suitable material through a sheet of carbon paper.

A spring 6 is placed inside of the tube 1 and rests with its lower end against the partly closed bottom portion of the tube, and with its upper end against the bushing 4.

With this arrangement the spring tends to

keep the plunger in a raised position with the upper tapered portion of the button 3 resting against the bottom end of the tube 1.

A second or outer tube 7 is placed on the 60 upper end of the tube 1. The upper end of the second tube is closed so that this tube forms an upper enclosure for the plunger 2 with the spring 6.

The tubes 1 and 4 are provided with 65 clamps 8 and 9 for attaching this device to the foot 10 of a hen. Each clamp consists of a resilient metal strip bent to suit the shape of the hen's leg. One end of the strip is pivotally attached to a lug 11 fastened to the tube 1, the other is adapted to engage a second lug 12. The free end of the clamp 8 or 9 is bent out forming a handle by which it may be snapped on or off the lug 12.

This device may be used in connection 70 with a simple record-receiving apparatus as shown in Figs. 1 and 2. This record-receiving apparatus or device consists of a cylinder 13 covered with a half hard rubber or 75 similar elastic material such as is used for ordinary typewriter cylinders. This cylinder is mounted on a shaft 14 the ends of which rest in slots 15 of a frame 16. This frame in the middle is pivotally mounted 80 on pins 17 supported on brackets 18. These brackets are fastened with screws 19 to a base plate 20. The rear end of the frame is formed with a heavy bar 21 which counter-balances the cylinder 13 and keeps it in 85 a raised position as shown in Fig. 1.

The cylinder 13 is provided on one end with a ratchet wheel 22 which is engaged by a pawl 23. The other end of this pawl is pivotally mounted on the side of the bracket 18.

The record-receiving device is placed on the ground near the exit aperture with a jumping bar 24 of a nest 25. This nest may be of an automatic type, such as is described 100 in my patent application Serial No. 196,541, filed June 4, 1927.

A cover or housing 26 is placed over the record-receiving apparatus and is provided with an exit aperture 27 for the hen. The cylinder 13 is placed in such position that the hen must jump on it before leaving the housing 26 through the aperture 27.

The drum 13 is covered with a sheet of paper or similar material, over which is 110

placed a sheet of carbon paper. A thin sheet of paper is placed over the carbon paper in order to protect it from being torn by the hen's feet. All these successive sheets are secured to the surface of the cylinder 13 by means of rubber bands 28.

The operation of my device is as follows.

The hen, after having laid an egg in the nest 25, finds the entrance aperture closed 10 and the exit open. She crawls through this aperture on the bar 24 from which she jumps on the cylinder 13 in order to get to the outer exit aperture 27. The cylinder under the weight of the hen moves down until it rests on the base plate raising the weight 21. At the same time the button 3 on account of its inertia slides down, overcom- 15 ing the spring tension, and strikes the surface of the cylinder 13. The figures 5 of the 20 button leave their impression on the paper from the carbon paper (or ink ribbon, if such was used).

When the hen leaves the cylinder in order to escape through the gate 27, the frame 16 with the cylinder 13 rise again to their operating position under action of the weight 25 of the bar 21. During this movement the pawl 23 causes the ratchet wheel 22 of the cylinder to move one or more notches, thereby exposing a fresh portion of the paper for the next hen.

Instead of using an individual record-receiving device for each nest, only one such device may be used at the exit from an enclosed yard in which all the hens who laid 35 their eggs are assembled. A suitable passageway or gates are placed in the box 25 in order to compel the hens to jump from the board 24 on the record-receiving cylinder 40 in order to escape from the enclosed yard.

Instead of the cylinder 13 a simpler device 45 may be used for obtaining impressions of the figure 5 of the button 3. This device may be made in the form of a pad 29 with a suitable resilient surface on which successive layers of writing paper, carbon paper and protective paper or cloth are placed (30, 31 and 32

respectively). The protective cloth 32 is mounted on a frame 33 and forms a cover fitting over the block or pad 29 and clamp- 50 ing down the sheets 30 and 31.

Another arrangement is shown in Fig. 9 in which the frame 34' has flanges on top to retain the sheets 30, 31 and 34, with an aperture exposing the loose protective sheet 55 34.

My invention provides a simple, reliable and automatic means for keeping account of egg-laying hens and thereby permits the operation of large chicken farms with but small 60 amount of labor.

I claim as my invention:

1. In an automatic recording device for hens, the combination with a printing member, a resilient means to support said printing member in an inoperative position, means to attach said supporting means with 65 said printing member to a hen's foot, said printing member being adapted to move down into an operating position when said hen jumps from her nest.

2. In an automatic recording device for hens, the combination with a printing member, of means to support said printing member, means to attach said supporting means with said member to a hen's foot, said printing member being adapted to move down into an operating position under action of the force of inertia, said supporting means being adapted to retrieve said printing member back into inoperative position when said inertia force ceases to act. 75

3. In an automatic recording device for hens, the combination with a printing member of a tubular member slidably supporting said printing member, means to attach said tubular member to a hen's foot, and a spring adapted to keep said printing member in an inoperative position and to let said printing member slide down when said hen jumps 85 90 from her nest.

Signed at New York in the county of New York and State of New York.

THEODORE P. GARANKIN.
